UNITED STATES PATENT OFFICE

2,047,815

CIRCUIT BREAKER

Winfield A. Atwood, Lansdowne, Pa., assignor to
General Electric Company, a corporation of
New York

Application April 25, 1933, Serial No. 667,855

9 Claims. (Cl. 200—116)

My invention relates to circuit breakers, more particularly to circuit breakers of the type known as branch circuit circuit breakers which provide the protective features characteristic of a fuse as well as the additional advantages of a manually operated switch, and has for an object the provision of a simple, reliable and inexpensive circuit breaker of this character.

Heretofore, branch circuit breakers have been provided with a thermal release arranged to trip the circuit breaker upon the occurrence of an overload, and with a manually operable handle for opening and closing the circuit independently of the thermal release. However, much is yet to be desired in such circuit breakers hitherto proposed to replace fuses because of the fact that the arc has been extinguished by means of magnetic blowouts and the like with resulting flame and arc gases. Inasmuch as branch circuit breakers, as applied to panelboards for the protection of lighting circuits, are called upon to interrupt currents of very considerable magnitude, it will be apparent that a considerable quantity of arc gases are generated and that the flame of the arc is quite appreciable. These two features are very undesirable in circuit breakers for household use. Furthermore, since the fuses which have hitherto been used accomplish this interruption of the circuit without spurts of flame, and without loud popping accompanying the interruption of an overload current of high magnitude, a satisfactory circuit breaker should also possess these advantages.

In carrying out my invention in one form thereof, I provide a circuit breaker which is capable of interrupting overload currents of large magnitude without the emission of flame, or arc gases, and without noise, by enclosing the contacts in a sealed steel chamber of restricted volume. More specifically, I provide a mechanism for both closing and opening the contacts with a snap action as well as one which opens the contacts with a snap action in response to overload current. The contacts move within the sealed metallic chamber so that when an arc is drawn between the separating contacts the pressure within the chamber increases quite rapidly. This pressure may be of the order of 1000 pounds per square inch. The resistance of the arc increases rapidly with pressure so that as the pressure is built up the resistance becomes so great that the arc can no longer exist, and it is extinguished.

For a more complete understanding of my invention, reference should now be had to the ac-

companying drawing wherein I have shown diagrammatically in Fig. 1 a side view, partly in section, of a circuit breaker embodying my invention; Figs. 2 and 3 show the different positions of the circuit breaker of Fig. 1, while Fig. 4 shows an end view of the circuit breaker of Fig. 1.

Referring to the drawing, I have shown my invention in one form as applied to a branch circuit breaker suitable for lighting circuits. The breaker is mounted on a base 10 of molded insulation which forms a support for the operating mechanism as well as for the arc interrupter 11.

The arc interrupter or compression chamber 11 is inserted within an enclosure 12 molded integrally with the base 10. The particular form 15 of arc interrupter or compression chamber 11 forms no part of the present invention, as it is fully described and broadly claimed in a pending application Serial No. 667,856 filed April 25, 1933, Walle, entitled "Circuit breaker" and assigned to the same assignee as the present invention. In the present application the compression chamber will be described by saying that it comprises a steel cylinder 14 within which a pair of insulating members or bushings 15 and 16 extend. The steel cylinder and the insulating members are so arranged as to provide a sealed chamber of relatively small volume. The contact members 17 and 18, formed of suitable arc-resisting material, are supported in spaced relation 20 with the steel cylinder by the respective bushings 15 and 16. When the contact 18 is moved to the open position relative to the stationary contact 17, the arc drawn between them causes a rapid increase in the air pressure within the 25 chamber.

In order to produce a strong and rigid construction, the bushings 15 and 16 are inserted into the ends of the steel cylinder. The ends of the cylinder are then swaged over the extensions 21 and 22 so that a very rigid construction of the arc chamber is produced. The stationary contact member 17 is provided with screw threads 24 which cooperate with a threaded member 25 forming a part of a conductor 26. 40 The insulating bushing 16 permits the reciprocal longitudinal movement of the movable contact member 18. A leather sealing washer 30 is provided around the movable contact member 18, 45 the washer being provided with an inwardly projecting cylindrical extension 31 which performs an important function in the operation of the circuit breaker. Since a certain amount of metal vapor is produced when the circuit breaker in- 50 55

interrupts current of large magnitude, it is necessary to prevent this metal vapor from collecting on the movable contact member 18 where it may harden and interfere with successive operations of the circuit breaker. The leather washer with its inwardly extending projection tends to prevent this collection of metallic vapor and cleans off any loosely adhering particles when the contact rod passes through the washer 10 when the breaker is opening the circuit. The washer furthermore assists in maintaining a substantially air-tight connection around the movable contact member 18.

As soon as the arc is drawn between the contacts 17 and 18, the pressure within the chamber of the arc interrupter increases rapidly. The potential drop across the arc is not entirely dependent on the rise in pressure inasmuch as the cross sectional area of an arc is approximately proportional to the current. It is believed that the arc drop is approximately proportional to the inverse square root of the current. This characteristic of the arc, in addition to the rise in pressure in the chamber, causes a quick interruption of the circuit. Furthermore, since the rise in pressure with a given volume depends upon the magnitude of the current interrupted, it will be seen that the greater the overload current the more quickly will the pressure rise to a point where the arc resistance becomes so great that the arc can no longer exist. This pressure also exerts an explosive action on the movable contact 18 accelerating its movement to the open circuit position.

Continuing with the operation of my invention, 35 the operating mechanism is supported from the base 10 by means of a U-shaped support or frame 45. Extending at right angles from the upper ends of the upright legs of the frame are a pair of outwardly projecting extensions 46, which extensions are provided with notches 46a for engagement with projections 47 molded integrally with the enclosure 12. The frame 45 is secured, by screws 48 extending through the base 10, in a position such that the vertical portion 49 of the 40 frame abuts a closure member 50. The frame, therefore, performs the functions of maintaining the closure 50 in place, supporting the operating mechanism and absorbing the blow incident to the expulsion of the movable contact 18 from the 45 compression chamber.

The reciprocal longitudinal movement of the contact member 18 is obtained by means of a pair of over-center springs 52, which springs have their corresponding upper ends carried by projections 54 secured on opposite sides of the operating handle 55. The opposite ends of the springs are secured to a pin 57 extending through an aperture in the movable contact 18 near its end. The operating handle 55 is secured to an inverted 60 U-shaped operating member 55a which in turn has its legs mounted on the portion of a pivot pin 62 extending outwardly beyond the legs of the frame 45. When the operating handle is moved from its left-hand position, shown in Fig. 1, to 65 its right-hand position, shown in Fig. 3, the movable contact 18 is moved from its open circuit position to closed circuit position with a snap action. The reciprocal longitudinal movement of the movable contact 18 is insured by a member 60 comprising two parallel legs connected together by a mid-cross portion 60a, which legs are mounted on the pivot pin 62 while their lower ends are pivotally secured to the pin 57. Since the lower end of the member 60 moves in a curved 70 path about the pivot 62, the opening in the mov-

able contact member 18 through which the pin 57 extends is elongated in a vertical direction; i. e., in the direction of the pivot pin 62 so that sufficient lost motion is obtained in a vertical direction to provide for freedom of movement of the pin 57.

In case of overload, a bimetallic thermal element 65, which is U-shaped, as shown in Fig. 4, and connected in circuit with the switch contacts so as to be heated by the current passing through the breaker, is caused to flex away from a latch 70 to permit a quick opening of the circuit. It will be observed that the latch 70 is supported by a tripping member 71 which is mounted on the pivot pin 62. The member 71 has a notch 72 into which extends a rod 73 into abutting relation with the member 71. A compression spring 75 encircles the rod 73 and has one end normally engaging a stop member 76 secured to the extension 46 of the frame 45 while the other end is arranged to engage a member 78 secured to the rod 73. As shown in Fig. 3, the contacts are closed and the tripping spring 75 is restrained under compression. As soon as the thermal element 65 releases the latching member 70, it will be observed that the force exerted by the tripping spring 75 is applied to the member 71 at the notch 72. This force urges the tripping member 71 in a clockwise direction around its pivot 62. The lower end 78a of the tripping member 71 engages the connection 60a between the parallel legs of the member 60, which member, it will be remembered, is connected to the movable contact 18. The spring 75 in rotating the member 71 in a clockwise direction quickly operates the contact 18 to its open circuit position as shown in Fig. 2.

An indication that the circuit breaker has been tripped is obtained by providing a projection 79 on the tripping member 71, which projection is located just below the extensions 71a and 71b forming a part of the operating handle 55. An opening 80 is provided in the extension 71b. The relative movement of the tripping member 71 from the positions shown in Fig. 3 to the position shown in Fig. 2 brings a suitably colored portion 40 on the projection 79 into registering relation with the opening 80 so that an indication is given that the circuit breaker has been tripped by an overload to its open circuit position.

In order to close the circuit breaker, after it 50 has been opened by overload as just described, the handle 55 is first moved in a counter-clockwise direction from the on position shown in Fig. 2. An extension 85 formed integrally with the operating member 55a strikes the tripping member 71 and thereby rotates the tripping member in a counter-clockwise direction until the latching member 70 is again returned to the latched position as shown in Figs. 1 and 3. Again referring to Fig. 2, it will be seen that as 55 the handle 55 is moved from the on position to the off position, the over-center springs 52 cross the pivot pin 62 so that the bias applied to the handle is in the direction to move the handle toward the off position. The bias of the spring 52, 60 applied through the handle to the tripping member 71, tends to rotate the tripping member 71 towards its first or latched position. The effort required in resetting the breaker is therefore only the difference between the biasing forces exerted 65 on the tripping member 71 by the springs 75 and 52. The switch closing operation is then completed by operating the handle 55 in a clockwise direction to the position shown in Fig. 3. A second projection 87 formed on the operating mem- 70

ber 55a strikes the frame 45 at the point indicated by the reference numeral 90 and acts as a stop for the operating member 55a.

While I have shown a particular embodiment 5 of my invention, it will be understood, of course, that I do not wish to be limited thereto since many modifications may be made, and I, therefore, contemplate by the appended claims to cover any such modifications as fall within the true 10 spirit and scope of my invention.

What I claim as new and desire to secure by Letters Patent of the United States is:

1. A circuit breaker comprising a stationary contact and a movable contact operable between open and closed circuit positions, an operating mechanism comprising a U-shaped frame having a pivot extending through its upper portion, a U-shaped operating member mounted on said pivot, a pair of spaced parallel arms having adjacent ends mounted on said pivot and having their other ends pivotally connected to said movable contact, said movable contact being provided with a slot to provide lost motion between said movable contact and said arms, an over-center spring having its respective ends connected to said operating member and said movable contact for operating said movable contact between open and closed circuit positions with a snap action, a tripping member mounted on said pivot and nesting between said spaced arms and said U-shaped member, a tripping spring normally biasing said tripping member from one position to a second position, a bimetallic thermal element for latching said tripping member into said one position against the bias of said spring whereby upon the occurrence of an overload said thermal element releases said tripping member to operate said movable contact to said open circuit position under the influence of said 40 tripping spring.

2. The combination with a circuit breaker provided with a stationary contact and a movable contact, of an operating mechanism for operating said movable contact between open and closed circuit positions with a snap action, comprising a U-shaped frame, a pivot extending through the adjacent arms of said frame, a U-shaped operating member mounted on said pivot and embracing said frame, said operating member being provided with a stop and an extension forming a reset member, a pair of over-center springs having their opposite ends connected to said operating member and said movable contact for operating said movable contact with a snap action, a pair of parallel spaced arms having adjacent ends mounted on said pivot and nesting within the arms of said frame and having their other ends pivotally connected to said movable contact member, a cross member connecting said arms together, a tripping member pivoted to said shaft and nesting between said arms, said tripping member being arranged to engage said cross member, a tripping spring for biasing said tripping member against said cross member so as normally to bias said contacts to said open circuit position, a thermal element for normally latching said tripping member out of engagement with said cross member so that said operating member is free to operate said circuit breaker independently of said tripping member, said reset member being operable by said operating member into engagement with said tripping member to rotate the same against its bias into its latched position.

75 3. A circuit breaker comprising relatively mov-

able contacts, an operating mechanism therefor comprising a frame having a pivot pin extending through its upper portion, an operating member mounted on said pivot pin, an operating arm having one end mounted on said pivot pin and its other end pivotally connected to one of said contacts, said pivotal connection being provided with a slot, an over-center spring having its respective ends connected to said operating member and said one contact for operating said contact 10 between open and closed circuit positions with a snap action, a tripping member mounted on said pivot pin, a tripping spring normally biasing said tripping member from one position to a second position, a bimetallic thermal element responsive to the current in said switch for latching said tripping member into said one position against the bias of said spring whereby upon the occurrence of a predetermined current in said switch said thermal element releases said tripping member to operate said movable contact to said open circuit position under the influence of said tripping spring.

4. A circuit breaker comprising a stationary contact and a movable contact operable between open and closed circuit positions, a frame having a pivot extending through its upper portion, an operating member mounted on said pivot, an arm having one end mounted on said pivot and its opposite end pivotally connected to said movable contact, said movable contact being provided with a slot to provide lost motion between said movable contact and said arm, an over-center spring having its respective ends connected to said operating member and to said movable contacts for operating said movable contact between open and closed circuit positions with a snap action, a thermal element connected in circuit with said contacts, a tripping member mounted on said pivot having one portion arranged to engage said arm and a second portion for latching said member in one position and arranged to be freed by operation of said thermal element, and a tripping spring normally biasing said tripping member from said one position 45 to a second position whereby upon the occurrence of a predetermined overload said thermal element releases said tripping member to operate said arm and said movable contact to said open circuit position, a third portion of said 50 tripping member indicating the overload tripping of said circuit breaker.

5. A circuit breaker comprising a switch operating arm movable between open and closed circuit positions, a frame, means pivotally mounting said operating arm on said frame, a manually operable handle member pivotally mounted on said frame, an over-center spring connected to said handle member and to said switch arm for operating said switch arm between said open 60 and closed circuit positions with a snap action, a tripping member pivotally supported on said frame, a tripping spring normally biasing said tripping member from one position to a second position, and current responsive means for holding said tripping member in said one position against the bias of said tripping spring whereby upon the occurrence of a predetermined current said current responsive means releases said tripping member, said tripping member being arranged to operate said switch arm to said open circuit position under the influence of said tripping spring.

6. A circuit breaker comprising a switch mem- 75

ber movable between open and closed circuit positions, an operating mechanism therefor comprising a frame, an operating arm, means pivotally mounting one end of said operating arm on said frame, means connecting the other end of said operating arm to said switch member, an operating member pivotally mounted on said frame, an over-center spring having its respective ends connected to said operating member and said switch member for operating said switch member between said open and closed circuit positions with a snap action, a tripping member pivotally supported on said frame, a tripping spring normally biasing said tripping member from one position to a second position, overload current responsive means for holding said tripping member in said one position against the bias of said tripping spring whereby upon the occurrence of a predetermined overload said over-load means releases said tripping member, said tripping member being arranged to operate said switch member to said open circuit position under the influence of said tripping spring, and means operated by said operating member for engaging and returning said tripping member to said one position.

7. A circuit breaker comprising relatively movable contacts, an operating mechanism therefor comprising a frame, an operating member pivotally supported on said frame, an operating arm one end of which is connected to one of said contacts and the other end of which is pivotally supported on said frame, an over-center spring having its respective ends connected to said operating member and to a point on said operating arm remote from the end supported on said frame for operating said contact between open and closed circuit positions with a snap action, a tripping member pivotally supported on said frame, a tripping spring normally biasing said tripping member for movement from one position to a second position, overload means responsive to the current through said contacts for latching said tripping member in one position against the bias of said tripping spring whereby upon the occurrence of a predetermined current through said contacts said overload means releases said tripping member for operation from said one position to said second position, said tripping member being arranged to engage said operating arm to operate said one of said contacts to said open circuit position irrespective of the position of said overcenter spring, and means operative by said operating member after said overload tripping of said tripping member for returning said tripping member to said one position against the bias of said tripping spring.

8. A circuit breaker comprising a switch mem-

ber movable between open and closed circuit positions, an operating handle movable between on and off positions, an over-center spring connected between said operating handle and said switch member for operating said switch member with a snap action to said closed circuit position when said handle is moved from said off to said on position, a tripping member, a tripping spring normally biasing said tripping member from one position to a second position, said tripping member when moved from said one position to said second position causing the operation of said switch member to said open circuit position irrespective of the position of said operating handle, and a connection between said handle and said tripping member for positively returning said tripping member to said first position when said handle is moved from said on to said off position, said over-center spring during a substantial portion of said movement acting in opposition to said tripping spring to minimize the effort required to return said tripping member to said first position.

9. A circuit breaker comprising a switch member movable between open and closed circuit positions, an operating mechanism therefor comprising an operating handle movable between on and off positions, an overcenter spring one end of which is connected to said switch member and the other end of which is connected to said operating handle for operating said movable switch member between open and closed circuit positions with a snap action in response to movement of said operating handle between on and off positions, a tripping member, a tripping spring normally biasing said tripping member from one position to a second position, overload current responsive means for restraining said tripping member in said one position against the bias of said tripping spring whereby upon the occurrence of a predetermined overload said over-load means releases said tripping member for operation from said one position to said second position, and means operable by said tripping member to operate said switch member to said open circuit position independently of said overcenter spring, means operable by the movement of said handle from said on position to said off position for returning said tripping member to said one position, said over-center spring acting during a substantial portion of the movement of said handle from said on to said off position against said tripping spring so that the effort required to return said tripping member to said one position is the difference between the biases exerted on said tripping member by said springs.

WINFIELD A. ATWOOD.
